US00D788141S

(12) **United States Design Patent** (10) Patent No.: **US D788,141 S**
 Kim et al. (45) Date of Patent: ** May 30, 2017

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Sora Kim**, Seoul (KR); **Cheolhoon Kang**, Seoul (KR)

(73) Assignee: **SAMSUNG ELECTRONICS CO., LTD.**, Gyeonggi-Do (KR)

(**) Term: **15 Years**

(21) Appl. No.: **29/549,547**

(22) Filed: **Dec. 22, 2015**

(30) **Foreign Application Priority Data**

Aug. 12, 2015 (KR) 30-2015-0040590

(51) **LOC (10) Cl.** **14-04**

(52) **U.S. Cl.**

USPC **D14/486**

CLAIM

We claim, the ornamental design for a display screen or portion thereof with graphical user interface, as shown and described.

DESCRIPTION

The FIGURE is a front view of a display screen or portions thereof with graphical user interface, showing our new design.

The broken line showing of the display screen or portion thereof and graphical user interface are included for the purpose of illustrating environmental structure and portions of the article and form no part of the claimed design.

1 Claim, 1 Drawing Sheet
